James Dickey, Pierce & Hann
ATTORNEYS

UNITED STATES PATENT OFFICE

ROBERT A. SHAW, OF DETROIT, MICHIGAN

SAFETY CURTAIN FOR PRESSES

Application filed June 23, 1930. Serial No. 463,339.

Although a specific use of the present invention is indicated by the above title, it should not be overlooked that the principles of said invention may render the same somewhat generally applicable. For example, the device may be used upon machines, of press type, that include, in addition to upright frame elements and a fixed or movable platen, a reciprocating element or elements having a powerful movement of approach relatively to said platen; and it is a merit of the present invention that its parts are such as may be either built into machines of the general type referred to or of other types or applied thereto subsequently to manufacture.

More specifically, it is an object of the present invention to provide a curtain or safety gate element, preferably comparatively light but substantially rigid, not only with means for elevating same in such a manner as to permit a hand feeding operation, when the mentioned reciprocating element is up, but also with means for lowering the same during the descent of said reciprocating element and at a comparatively high rate of movement, to afford warning or otherwise to occasion a due removal of an operative's hands from any position of danger.

Other objects of the present invention, in which the mentioned reciprocating element may be assumed to be manipulated by means comprising a connecting rod or rods and in which the manipulating means for the mentioned curtain may include a pair or pairs of sheaves of unequal diameter, rotatably supported from one or both of a pair of substantially vertical frame elements (a large sheave or sheaves being connected by flexible means with the mentioned curtain and a small sheave or sheaves being similarly connected with a connecting rod or rods) may be best appreciated from the following description of an illustrative embodiment of the invention, taken in connection with the appended claims and the accompanying drawing.

Fig. 1 is an elevational view of a press to

which an embodiment of the invention has been applied.

Fig. 2 is a vertical section, taken substantially as indicated by the line 2—2 of Fig. 1.

Referring first to the more conventional features of that embodiment of the present invention which has been selected for purposes of illustration, a one-piece or other frame upon a base 10 may include, in addition to a horizontal platen or lower connecting element 11 and an arcuate overhead connecting element 12, a pair of substantially vertical upright guide elements 13, 13' for a reciprocating element 14; and said reciprocating element is shown as manipulable by means including a crank-shaft 15, received in bearings 16, 16' that may be supported from the mentioned frame by means including a web 12'. Said shaft is shown as including an extension 17, projecting through the upright frame element 13' and provided with means, including a large gear 18, for imparting a comparatively slow powerful rotative movement thereto. This rotative movement may be transformed into a reciprocating movement of the element 14, or its equivalent, by means such as cranks 20, 20', provided upon the shaft 15, and connecting rods 21, 21', pivotally connected with said cranks and with said reciprocating element,—these being well known features of press construction.

Coming now to the more novel features of the present invention, a light but rigid curtain element 22 is shown as dependently supported by flexible means including ropes or equivalent linear tension elements 23, 23' (which may be secured thereto by means such as staple-like U bolts 24, 24'); and the upper or remote ends of the flexible elements 23, 23' are intended in all cases to be connected with means for imparting thereto a more extensive and more rapid movement of reciprocation than that which may be imparted to the reciprocating element 14 through the connecting rod or rods 21, 21' or other means of manipulation.

For the purpose last referred to, an additional pair of tension elements 25, 25' being shown as attached (by means optionally

- including threaded posts 26, 26' and hooks or rings 27, 27') to the upper ends of the connecting rods 21, 21', like pairs of sheaves, 28, 28' and 29, 29' may advantageously be 5 supported in an out-of-the-way position and at an intermediate level,—as by means of shafts 30, 30', supported in brackets 31, 31', the latter being optionally secured to the respective side or guide posts 13, 13' above the 10 intended limits of movement of the reciprocating member 14 or out of the path of any guide elements 32, 32' provided thereon.
- The described construction will be seen to provide for the dependent support of a light 15 gate of curtain element, such as may be formed from or framed by inexpensive sheet metal, in such manner as to effect a timely upward withdrawal of the same to permit a manual introduction and removal 20 of any articles or materials, constituting the work, from between the platen 11 and the reciprocating element 14, or any equivalent part; and the ratio of the sheave or sheaves 28, 28' to the sheave or sheaves 29, 29' may 25 be such as to effect a timely and ample movement of the curtain 22, or its equivalent (a sheave ratio of 1 to 2 being suggested as suitable) and also such as to assure a prompt descent of said curtain, or its equivalent,— 30 into engagement with the arms of an operative, in case he is dilatory, in time to permit, and/or in such manner as to expedite a withdrawal thereof before the descent of the reciprocating element 14 shall be so far completed as to prevent such withdrawal. The 35 lateral positions of the mentioned sheaves and all parts connected therewith will be seen to obviate obstructions to the use of the press, or any equivalent machine or unit, in a customary manner.
- Obviously the guarded opening may be 40 totally different from that shown; light and dependent or otherwise easily movable curtains or safety gates of the described 45 type may be used with alternative motion-multiplying means; the sheaves constituting a united pair, when sheaves are employed, may have any desired ratio and may be variously spaced apart and disposed, according 50 to conditions involved; and either gravity or spring action may be relied upon yieldably to bring curtains or gates, one or more to a machine, either to or from a safeguarding position relatively to an opening 55 or to moving parts; but the weight and the mode of manipulation of each gate and its relationship to other fixed parts and motion-imparting parts are intended always to be such as to give notice or to expedite or ob- 60 struct some movement with a view to obviating risk of e. g. pinioning a worker's limbs in any position of danger. It is primarily for this last-mentioned reason that flexible means and light materials are employed in 65 its manipulation and construction of the

gates, the latter being preferably foraminous or translucent in order to permit the operative to get a clear view of the work at all times.

No duplication of gates at the front and/or rear of a machine or furnace or other unit may ordinarily be required; but it should be noted that a single small sheave may be secured on the same shaft with either one or two or more large sheaves,—each connected with one or more ropes running to near or remote gates; and within limits, these sheave organizations and gates may be provided in a series of standardized sizes, to be applied by the purchaser as they may be needed. If desired, each may include a guide eye 33 and/or provide a plurality of alternative bearing openings for shafts 30, 30'.

Although the foregoing description has included complete details of but one embodiment of the present invention, it will be understood not only that various features thereof might be independently employed, but also that numerous modifications, additional to any suggested herein, might easily be devised by skilled workers, if informed of the foregoing,—all without departure from the scope of the present invention, as the latter is indicated above and in the following claims.

What I claim is:

1. In a hand-fed power-driven machine of press type comprising a platen element disposed between upright frame elements and adapted to cooperate with a reciprocating element, a safety organization comprising: a curtain element; and means for so reciprocating the same in front of said platen element as to occasion timely withdrawal of an operative's hand from between said platen element and said reciprocating element,—said reciprocating element being movable by means including a pair of connecting rods and said last mentioned means including pairs of sheaves respectively rotatably supported from said upright frame elements, and including also flexible elements extending from said sheaves to said connecting rods and to said curtain element to permit the movement of the curtain element away from said platen element.

2. The combination with a hand-fed power-driven machine of the press type including, in combination, a work receiving table and a ram reciprocable toward and away therefrom, of a guard for said machine, cables supporting said guard, sheaves about which said cables are secured, additional sheaves secured to said first said sheaves and actuated by cables in accordance with the movement of said ram, and guides for said cables for retaining said guards in predetermined position and permit said guards to

be freely swingable away from said table and ram.

3. For use in a safety device of the general character described: a view-permitting gate formed of a light material and provided with flexible means for its support and manipulation in a vertical plane, and guides for engaging said flexible members and positioning said gate in such manner as to have the gate freely movable outwardly of said vertical plane.

4. For use in the manipulation of a gate of the general character described, a motion-

multiplying device comprising: a shaft; a plurality of sheaves differing in size, secured thereon; and flexible means extending from said sheaves respectively toward a motion-imparting member and toward said gate for effecting a differential movement to said gate, and guides for engaging said flexible members and positioning said gate in such manner as to have the gate freely movable outwardly of said motion-imparting member.
